UNITED STATES PATENT OFFICE

WILLIAM HAROLD MINER, OF SPRINGFIELD, MASSACHUSETTS, ASSIGNOR TO BAUSH MACHINE TOOL COMPANY, A CORPORATION OF MASSACHUSETTS

MULTIPLE-SPINDLE DRILLING MACHINE

Application filed June 24, 1927. Serial No. 201,174.

My invention aims to provide a machine of simple and economical construction.

The accompanying drawings illustrate an embodiment of the invention.

5 Fig. 1 is a side elevation of the machine;

Fig. 2 is a plan of the same on a reduced scale;

Fig. 3 is a longitudinal vertical section, with parts in elevation;

10 Fig. 4 is a partial transverse vertical section;

Fig. 5 is a horizontal section through the head of the machine;

Fig. 6 is a section approximately on the 15 line 6—6 of Fig. 1;

Fig. 7 is a section on the line 7—7 of Fig. 3.

The column 1 and bed 2 are cast integrally. The spindle carrying head 3 is cast in one piece with the gear chest 4 which is 20 mounted on the top of the column and fastened by the usual dowels and screws. On top of the gear chest is a cover 5 on which is mounted the motor 6 with a vertical shaft 7. The drill spindles 8 are set in adjustable 25 position by means of arms 9 mounted on the underside of the head 3, the spindles being driven through the usual flexible connections 10 leading to shafts 11 having bearings in a lower wall 12 of the gear chest and carrying at their upper ends pinions 13 arranged in a circle about a driving gear 14, journaled on a fixed shaft 15 which has bearings in the wall 12 of the chest and in the 30 cover 5.

35 The shaft 7 of the motor carries at its lower end a pinion 16 which drives a gear 17 mounted on a shaft 18 having bearings in the cover 5 and in the lower wall 12 of the chest. The gear 17 has a driving connection with a 40 worm 19 on the same shaft. A horizontal shaft 20 has a worm gear 21 driven by the worm 19. The shaft is mounted in bearings in vertical walls in the gear chest and has keyed to its forward end a worm 22 45 which drives a worm gear 23 journaled on the shaft 15. This worm gear is fixed to the central spindle-driving gear 14.

The shaft 20 near its rear end carries a worm 24 driving a worm gear 25 which is 50 mounted on the vertical shaft 26 which ac-

tuates the feed of the machine. The shaft 26 has bearings in the lower wall 12 of the gear chest and in the cover 5 as shown in Fig. 4 and extends vertically through the column 1, having its lower end in bearings on the column and the base 2, as shown in Fig. 4. Near its lower end the shaft carries a worm 27 which engages a worm gear 28 which is journaled on a shaft 29 extending to the front of the machine. A clutch sleeve 30, Fig. 3, is keyed on the shaft and may be shifted to engage a clutch block 31 on the gear 28 to cause the rotation of the shaft. The clutch is actuated by a forked lever 32 pivoted on a shaft 33 extending transversely through the machine (Fig. 6) and carrying at its outer end a handle 34 which has a recessed lug 35 carrying a spring pressed ball 36 adapted to engage a notch in the plate 37 mounted on the side of the column so as to hold the handle in the raised position of Fig. 1, which is the position for driving the cross shaft 29.

On the front of the lower end of the column, there is a work-holding table 38 of the knee type which has a sliding engagement with the column. The sides of the table overlap the flanges 39 of the column as shown in Fig. 7, and carry plates 40 overlying the rear faces of the flanges so as to guide the table vertically. The table is fed by means of a cam 41 keyed on the forward end of the shaft 29 and bearing on the underside of a roller 42 fixed in the lower end of a tubular post 43 which forms an adjustable part of 85 the work-table, and which should be located directly in line with the centre of the working surface of the table.

While the handle is lifted and clutch on the cam shaft is engaged, the table moves continuously, the cam lifting it and the weight of the table and fixtures holding the roller 42 down on the cam. The cam should be shaped according to the job in hand to give the usual quick approach, slow feed, quick return and dwell. The table is brought to rest by throwing out the clutch by lowering the hand lever 34.

The table is adapted for a vertical adjustment by means of a shaft 44 threaded through 100

the upper part of the hollow post 43, journaled in the top plate of the table and carrying a beveled gear 45 which is driven by a pinion 46 on a shaft 47 extending through the 5 front of the table and having its outer end squared for engagement by a crank.

The drill spindles and cam are thus run from a common driving shaft and at a substantially constant speed. The speed of the 10 spindles can be altered by changing the ratio between the spindle pinions 13 and their driving gear 14. The speed of the feed cam can be altered when the machine is built by using different single or multiple thread worms 15 for driving the worm gearing at the top and the bottom of the vertical feed shaft 26. Being set to take care of a particular job, the machine can be operated at a high rate of 20 production. It is of very simple design and comparatively few parts so that it can be operated with a comparatively small expenditure of power.

Various modifications may be made by those skilled in the art without departing 25 from the invention as defined in the following claims.

What I claim is:

1. A multiple spindle drilling machine which comprises a column, a spindle carrying 30 head, a gear chest at the top of said column, a work table, a cam for feeding the table, a horizontal cam shaft for rotating said cam, a vertical shaft, transmission gears for driving said horizontal shaft from said vertical shaft, said vertical shaft extending upwardly into said gear chest, a horizontal shaft in said gear chest, a main driving means driving said horizontal shaft, a multiple drill carrying spindles, a driving gear, gears on said spindles driven from said driving gear, a worm gear on said main driving means, a worm on said horizontal shaft meshing with said worm gear, a worm gear on said vertical shaft within said gear chest, and a worm on said horizontal shaft meshing with said worm gear on said vertical shaft.

2. A multiple spindle drilling machine which comprises a column, a spindle carrying head, a gear chest at the top of said column, a work table, a cam for feeding said work table, means for adjusting the position of said work table relative to said cam at any position of said cam, a horizontal cam shaft for rotating said cam, a vertical shaft, gears between said vertical shaft and said cam shaft, means for clutching and unclutching said gears to said horizontal cam shaft, said vertical shaft extending upwardly into said gear chest, a horizontal shaft in said gear chest, a main driving means for driving said horizontal shaft, a multiple drill carrying spindles, a driving gear, gears on said spindles driven from said driving gear, a worm gear on said main driving means, a worm on said horizontal shaft meshing with said worm

gear, a worm gear on said vertical shaft within said gear chest, and a worm on said horizontal shaft meshing with said worm gear on said vertical shaft.

In witness whereof, I have hereunto signed my name.

W. HAROLD MINER.
